UNITED STATES PATENT OFFICE.

CHARLES H. JOHNSON, OF COLONY, KANSAS.

PRINTING-PRESS.

SPECIFICATION forming part of Letters Patent No. 748,743, dated January 5, 1904.

Application filed July 30, 1901. Serial No. 70,239. (No model.)

To all whom it may concern:

Be it known that I, CHARLES H. JOHNSON, a citizen of the United States of America, residing at Colony, in the county of Anderson 5 and State of Kansas, have invented certain new and useful Improvements in Printing-Presses, of which the following is a specification.

This invention relates to printing-presses, 10 and particularly to that class known as "bed-and-cylinder machines," the said invention being a part of the application filed March 20, 1900, which has been divided.

The object of the invention is to produce, 15 first, a novel combination for moving the impression-roll vertically; second, for operating the gripping-fingers and temporarily retaining them in position, and, third, for reciprocating the type-bed.

20 In describing the invention in detail reference will be had to the accompanying drawings, forming a part of this specification, wherein like characters denote corresponding parts in the several views, and in which—

25 Figure 1 is a longitudinal central sectional view of a printing-press embodying the invention. Fig. 2 is a longitudinal sectional view of a portion of the invention shown in Fig. 1. Fig. 3 is a transverse sectional view 30 taken in front of the impression-roll.

In the drawings, 1 denotes the frames, and 35 2 a crank-handle of a shaft on which the drum 3 is mounted and by which it is rotated. A type-bed 25 has depending ribs *a*, which travel in the tracks 13 of the frame. The bed-plate has a forwardly-projecting arm 34, provided 40 with a head, and the end of the head has slots in which is fastened the end of the strap *b*, the opposite end of said strap being wound around

45 the drum 3. A strap *b* has one end wound around the drum and its opposite end extending rearwardly and secured to the end of the arm 35, said arm being attached to the rear of the type-bed. It will be observed that as the 50 drum is rotated in alternate directions the straps will impart a reciprocating movement to the type-bed.

Approximately midway the length of the frame are brackets 27, each having apertured 55 ends for receiving a rod *c*, said rod having in its upper end a bearing 3' of the type-inking roll 3'.

A feeding-table 7 is supported by the standards 26 and 39.

The ink-fountain 44 is attached to the rear 55 of the frame of the press, and a roll 19 therein is engaged by the inking-roll 31^a when the inking-plate 37 moves forward with the bed-plate to which it is attached. A distributing-roll 31^b is suitably journaled to engage 60 the surface of the inking-plate in its movement. An elongated bearing 20 is provided for the roll 31^a in order that said roll may descend into engagement with the roll 19 when disengaged by the inking-plate. An arm 4 65 is also secured to the shaft 21 of the frame and carries at its upper end a wheel 40, which is engaged by a rib 41, depending from the under surface of the bed-plate. The arm 4 is held normally in the position shown in full 70 lines, Fig. 2, by the action of the spring 29, and when in such position the dogs 9^b engage the lower ends of the rods 5 and elevate said rods. The rods in turn elevate the bearings 9, thus carrying the impression-roll 6 out of 75 engagement with the type as the type-bed moves rearwardly. The bed moves a sufficient distance in one direction to permit the end 41^a of the rib 41 to pass beyond the roller 40 when said roller is in the full-line position 80 and in the opposite direction sufficiently to allow the end 41^b to pass beyond the roller 40 when said roller is in the position illustrated in dotted lines. After the end 41^b of the rib has passed beyond the roller and released it the spring 29 returns the arm 4 to 85 the position shown in full lines, Fig. 2. The roller 40 when released by either end of the rib is held by the arm 4 in the path of travel of the rib 41 through the action of the spring 90 29, the rods 5, and dogs 9^b.

The arms 34 and 35, attached to the type-bed, are of such length as to permit the ends of the rib to pass beyond the roller 40 in each direction.

A frame 15 is pivoted in the standards 9^a and has secured thereon the paper-rests 14. The frame 15 is rocked by a dog 8, having its depending member in the path of travel of the type-bed. A gripping-finger 33, suitably 100 operated, is also provided; but as the frame, paper-rest, dog, and gripping-finger form no part of the present invention a detail description is thought to be unnecessary.

Having thus fully described the invention, what I claim as new, and desire to secure by Letters Patent, is—

1. In a printing-press, a frame, a type-bed having a depending rib, a rock-arm, a spring attached to the arm and to the frame, a roller on the rock-arm engaged by the rib whereby the arm is oscillated, an impression-roll means whereby the movement of the arm is communicated to the impression-roll and means for moving the type-bed on the frame.
2. In a printing-press, a frame, a type-bed having a depending rib, a rock-arm, a spring attached to the arm and to the frame, a roller

on the rock-arm engaged by the rib whereby the arm is oscillated, an impression-roll means whereby the movement of the arm is communicated to the impression-roll, arms on the type-bed, a drum, and flexible connections attached to the arms and wound on the drum.

In testimony whereof I affix my signature, in the presence of two witnesses, this 25th day of June, 1901.

CHARLES H. JOHNSON.
